UNITED STATES PATENT OFFICE.

GEORGE H. LOMAX, OF SOMERVILLE, MASSACHUSETTS.

LANTERN.

SPECIFICATION forming part of Letters Patent No. 325,255, dated September 1, 1885.

Application filed June 17, 1885. (No model.)

To all whom it may concern:

Be it known that I, GEORGE H. LOMAX, of Somerville, in the county of Middlesex, of the Commonwealth of Massachusetts, have invented a new and useful Improvement in Lanterns; and I do hereby declare the same to be described in the following specification, and represented in the accompanying drawings, of which—

10 Figure 1 is a side view of a lantern provided with my invention, the nature of which is defined in the claims hereinafter presented. Fig. 2 is an under side view, and Fig. 3 a transverse section, on an enlarged scale, of the base-ring and oil-reservoir of such lantern.

15 In carrying out my invention the oil-reservoir or bottom portion of the lantern has projecting from it, at or near its central part, a screw to extend therefrom below the annular 20 or supporting base of such bottom portion, such screw being to allow of the lantern being screwed to a board, plank, or other device for supporting it. The said screw I hinge or so attach to the lantern-bottom as to enable the screw to be turned or moved within the 25 base in a manner to prevent the screw from extending beyond the base, and I have to the base a catch or device for holding the screw in its raised position, such catch or device admitting of the screw being turned down into a 30 position to cause it to project below the base in a manner to admit of the screw being screwed into a plank or other support by revolving the lantern.

35 Lanterns when simply standing on a surface without being confined thereto are liable to be accidentally overset; but with my improvement a lantern may be fixed firmly in place on a board or supporting device.

40 In the drawings, A denotes a lantern of common construction, *a* being its oil-reservoir, and *b* the supporting-flange or tapering ring extending down from it.

The fastening-screw is shown at *B* as projecting a sufficient distance below the base, and from one of the leaves of a common butt or door hinge, *C*, whose other leaf is fastened to the bottom *c* of such oil-reservoir, the screw

when in its lowest position being in the axis of the reservoir produced. The screw can be 50 turned upward against the said bottom, so as to be wholly within the space circumscribed by the base, there being affixed to the base a spring-catch, *D*, for holding the screw in its raised position. On turning upward the screw it 55 will be pressed against the elastic or yielding part *e* of the catch, and by friction on such will be held up. When the screw is down in its lowest position, it so projects beyond the base as to enable the screw to be screwed into 60 a board or other flat device by revolving the lantern over such board or device.

When the screw is folded or turned up into its highest position, it will be wholly within the base, so as not to prevent it from being 65 placed with its lower edge upon and fully in contact with a board or flat surface.

I claim—

1. A lantern provided or combined with a screw arranged within the annular supporting-base and projecting from and hinged to the bottom of such lantern, so as to be capable of being moved from a position at right angles to such bottom upward into another position parallel, or about so, with the bottom, such screw when in its lowest position projecting beyond the lower edge of the base, as set forth.

2. A lantern provided with a screw hinged to the bottom of such lantern, so as to be capable of being turned from a position at right angles with the said bottom into one parallel, or about so, therewith.

3. A lantern provided with an annular base extending from the bottom of the oil-reservoir, and provided with a screw pivoted or hinged to the said bottom, and also with a catch to hold the screw in its raised position, as set forth, the screw when turned down projecting beyond the said base, as and for the purpose 90 substantially as represented.

GEORGE H. LOMAX.
